(57) **CLAIM**

The ornamental design for an animal deterrent device, as shown and described.

DESCRIPTION

FIG. 1 is a front elevation view of an animal deterrent device showing a new design;

FIG. 2 is a rear elevation view thereof;

FIG. 3 is a right side elevation view thereof; and,

FIG. 4 is a left side elevation view thereof.

The dashed lines shown in the drawings are for environmental purposes only and form no part of the claimed design.
